UNITED STATES PATENT OFFICE.

HENRY C. YEISER, OF CINCINNATI, OHIO, AND WILLIAM A. RINGLER, OF PHILADELPHIA, PENNSYLVANIA, ASSIGNEES TO GLOBE WERNICKE CO., OF CINCINNATI, OHIO, A CORPORATION OF OHIO.

TRAY FOR MACHINE POSTING.

Application filed June 15, 1923. Serial No. 645,592.

To all whom it may concern:

Be it known that we, HENRY C. YEISER, a citizen of the United States, residing at Cincinnati, county of Hamilton, State of Ohio, and WILLIAM A. RINGLER, a citizen of the United States, residing at Philadelphia, county of Philadelphia, State of Pennsylvania, have invented a new and useful Tray for Machine Posting, of which the following is a specification.

Our present invention comprehends a novel construction and arrangement of a tray for machine posting.

It further comprehends a novel tray for machine posting wherein the compressor plates are mounted and locked in position in a novel manner.

It further comprehends a novel construction of a tray wherein one side is adjustable and wherein the center portion can be shifted to accommodate different sized sheets.

It further comprehends a novel construction of compressor plates which are permitted to move upwardly and which are locked in position by eccentric members and the plate carriers are held in position by the pressure of a clamp and channel against the flanges of a supporting channel.

Other novel features of construction and advantage will hereinafter more fully appear in the detailed description.

For the purpose of illustrating our invention, we have shown in the accompanying drawings embodiments thereof which are at present preferred by us, since these embodiments will be found in practice to give satisfactory and reliable results. It is, however, to be understood that the various instrumentalities of which our invention consists can be variously arranged and organized and that our invention is not limited to the precise arrangement and organization of these instrumentalities as herein shown and described.

Figure 1 represents a top plan view of a ledger tray for machine posting, embodying our invention.

Figure 2 represents a section on line 2—2 of Figure 1.

Figure 3 represents a section on line 3—3 of Figure 2.

Figure 4 represents a section on line 4—4 of Figure 3.

Figure 5 represents a section on line 5—5 of Figure 2, the filing unit and spacer channels having been removed.

Figure 6 represents, in end elevation, a portion of the tray.

Figure 7 represents, in perspective, a portion of the tray.

Figure 8 represents a section on line 8—8 of Figure 7.

Figure 9 represents a sectional view similar to Figure 8 but showing another embodiment of our invention.

Similar numerals of reference indicate corresponding parts.

Referring to the drawings.

1 designates the bottom of the tray to which are connected in any desired manner, for example, by welding, the foot angles 2, which are preferably provided with the rubber feet 3. The tray bottom 1 is preferably made of sheet-metal and is provided with a depressed portion 4, see more particularly Figure 5, thereby providing supporting lateral extensions 5. One lateral extension 5 has a portion directed upwardly, as indicated at 6, and connected with the tray side 7 which at its lower end is deflected inwardly and upwardly. The opposite lateral extension 5 forms a table and extends downwardly to contribute to form a side 8 which at its lower end is deflected inwardly and upwardly.

9 designates a side extension body in the form of side plates 10 which are connected to a front plate 11. The plates 10 are slideable on the table 5 and are offset, as at 12, see more particularly Figure 1. One of the sides 10 co-operates with a side angle 13 secured to one of the tray ends 14 by means of fastening devices 13' of any desired character. The latch 16 is pivotally carried by a side plate 10 and is adapted to interlock with the walls of one of the recesses 17 in the upwardly extending face of the side angle 13.

18 designates a stop which limits the inward movement of its respective side plate 10 and the latch-carrying plate 10 is preferably recessed on its under side to form a shoulder 19 and provide for the proper slid-

ing of the side extension body. Brace angles 20 are preferably welded or otherwise connected with the side plates 10 and the front plate 11, in order to provide for the proper 5 rigidity of the side extension body. Each end 14 is provided with a handle 15 and one end is provided with a label holder 16. 21 designates a center slide, the upper face of which is depressed in order to receive the 10 rod 22, the ends of which are carried by the upturned portions 23 of a center channel 24.

The slide 21 is in the form of an inverted U-shaped channel member which is slidable 15 within the center channel 24, the construction and arrangement of which will be best understood by reference to Figures 2, 7 and 8. This center channel 24 is provided with a bottom plate from which extends upwardly 20 the sides 25 which merge into lateral extensions 26 which are directed inwardly toward each other. Two of the slides 21 are employed which have the function of follower blocks and to each of these slides are welded 25 or otherwise secured two longitudinally extending plates 27 which are spaced from each other and connected with a top plate 28 welded or otherwise secured to the spaced plates 27. This top plate 28 at one end is 30 deflected upon itself to form a sleeve 29 to receive a brace wire 30, the sides of which diverge upwardly and outwardly and are connected by a cross piece which is movable in the guides 31 secured in any desired manner 35 to a compressor plate 32.

33 designates an eccentric fulcrumed at 34 on a compressor plate 32 and provided with an actuating handle 25. The eccentric 40 has its outer periphery grooved, as indicated at 36, in order that the cross bar of the brace wire will be received therein, as will be best understood by reference to Figure 4. Two compressor plates 32 are employed and each of such compressor plates 45 is provided with a grasping handle 37. The top plate 28 of a slide 21 is deflected at its inner end to form a sleeve 38, see Figure 7, and the lower end of a compressor plate is deflected to form the sleeves 39, said sleeves 50 being adapted to receive a rod 40, see Figure 2. Each slide is adjustable along the center channel and is adapted to be locked in its adjusted position. For this purpose, I provide for each slide an upwardly extending 55 screw 46 which passes through an inverted U-shaped cross bar 42 and through a spacing collar 43. The U-shaped cross bar 42 is in the form of a channel, the sides of which are recessed, as indicated at 44, see Figure 8, so that it will rest upon the flanges 26 of the center channel but will not contact with the top plate 28. Each screw 46 is provided with a wing nut 45 which bears against the top face of its respective cross bar 42. In 60 this manner, it will be apparent that each

slide can be readily locked in the position to which it has been adjusted.

It is advantageous in case the side extension body 9 is drawn outwardly to have the center channel and its adjuncts centrally positioned or centered within the tray. For this purpose I provide, as best seen in Figure 3, the members 47 in the form of channels which together with the adjusting strips 48, 49 and 50 form a false bottom. The adjusting strips 48, 49 and 50 are also in the form of channel members and may be of different dimensions.

The bottom of the tray is preferably provided with longitudinally extending strips of material 51 such as, for example, cork, which will tend to prevent sliding or slipping of the sheets which are supported thereon. If desired, the strip of suitable material such as, for example, felt, as shown at 52, see Figure 9, may be employed to serve as a filler, the cross bar 42 being recessed to receive such strip.

The operation of the tray will be readily apparent to those skilled in this art.

The slides can be adjusted in accordance with conditions and requirements met with in practice and the compressor plates can be locked firmly against the articles or sheets located therebetween by means of the eccentric cam mechanisms on the faces of the plates. When one cam mechanism is unlocked its compressor plate can be swung rearwardly or forwardly on its hinged lower end. One side of the tray can be adjusted so that the tray will accommodate articles or sheets of different widths and the center portion can be shifted owing to the provision of the adjusting members so that the tray will accommodate different sized sheets.

When a handle 35 is moved into its released position, the eccentric co-operates with a stop 53, see Figure 3, said stop having a curved contact face to conform to the periphery of the eccentric.

A tray for ledger posting constructed in accordance with our present invention can be supported on any desired type of stand when in use or can be assembled in a cabinet, and at the end of the day's work, the tray and its contents can be removed and locked up in a safe, if so desired.

The brace members are preferably in the form of spring wires so that they are resiliently locked in place and their upper portions will be moved resiliently toward each other so that a resilient clamping action is obtained against the cards, ledger sheets or other papers which are being posted. When the compressor plates are in locked position, it will be apparent that the articles filed are firmly locked with respect to the tray so that there is no possibility of sheets becoming misplaced or falling out of the tray in case the tray should be overturned.

The tray can be readily adjusted to receive sheets of different sizes as the compressor plates and their adjuncts are both longitudinally and laterally adjustable with 5 respect to the tray.

The parts can be economically manufactured from sheet metal and a very strong and rigid construction is produced.

It will now be apparent that we have devised a new and useful tray for machine posting which embodies the features of advantage enumerated as desirable in the statement of the invention and the above description, and while we have, in the present 10 instance, shown and described embodiments thereof which will give in practice satisfactory and reliable results, it is to be understood that these embodiments are susceptible of modification in various particulars 15 without departing from the spirit or scope 20 of the invention or sacrificing any of its advantages.

Having thus described our invention, what we claim as new and desire to secure by Letters Patent is:—

1. In a device of the character described, a frame, follower blocks slidable therein, locking mechanism for said follower blocks, compressor plates hinged to said follower 30 blocks, brace members hinged to said follower blocks, guides on said compressor plates through which said brace members pass; and which serve to retain such brace members in co-operative relation with said locking mechanism, and means cooperating 35 with said brace members to lock said compressor plates in closed position.

2. In a device of the character described, a frame, follower blocks slidable therein, 40 locking mechanism for said follower blocks, compressor plates hinged to said follower blocks, brace members hinged to said follower blocks, guides on said compressor plates through which said brace members 45 pass, and manually actuated eccentrics carried by said compressor plates and adapted to engage said brace members to lock said compressor plates in closed position.

3. In a device of the character described, 50 a tray having an extensible and a retractible side, means to lock such side in its adjusted position, sheet-locking mechanism in said tray, and means insertable between said sides to centralize said mechanism in accordance 55 with the extension or retraction of said side in order to accommodate different sized sheets.

4. In a device of the character described, 60 a frame having a plurality of adjusting members, a center channel positioned by said adjusting members, follower blocks guided by said center channel, compressor plates hinged to said follower blocks, means to lock said follower blocks in position, and

means to lock said compressor plates in 65 closed position.

5. In a device of the character described, a sheet-metal frame having a movable side to vary the size of said frame, means to lock said side in its adjusted position, follower 70 blocks relatively adjustable longitudinally of the frame, means to effect lateral adjustment of said follower blocks, compressor plates hinged to said follower blocks, and independent locking mechanism 75 for each compressor plate.

6. In a device of the character described, a sheet-metal frame having a portion of its bottom depressed, a sectional false bottom in said depressed portion, adjusting members seated in said depressed portion, a center channel positioned between said false bottom sections, a rod carried by said center channel, follower blocks slidable in said channel, locking mechanisms co-operating 80 with said rod to lock said follower blocks with respect to said rod, said frame having a laterally adjustable side, compressor plates hinged to said follower blocks, and means 85 to lock said compressor plates in closed position.

7. In a device of the character described, a frame, a center channel therein, follower blocks slidable with respect to said center channel, a rod carried by said center channel, means to lock said follower blocks with 90 respect to said rod and said channel, compressor plates hinged at their lower ends to said follower blocks, brace members hinged at their lower ends to said follower blocks, guides on said compressor plates 95 through which said brace members pass, and locking mechanism cooperating with said compressor plates and brace members to lock said compressor plates in closed position, said guides serving to retain said brace members in the path of said locking mechanism.

8. In a device of the character described, a frame, a channel therein, follower blocks guided by said channel, means to lock said follower blocks with respect to said channel, compressor plates hinged to said follower blocks, resilient brace members connected 110 with said follower blocks, guides on said compressor plates through which said brace members pass, and having relative movement with respect to said compressor plates, and manually actuated cam members 115 cooperating with said compressor plates and brace members to lock said compressor plates in closed position.

9. In a device of the character described, a frame, a channel positioned therein, follower blocks guided by said channel, means to lock said follower blocks with respect to said channel, compressor plates hinged at 120 their lower ends to said follower blocks,

brace members hinged at their lower ends to said follower blocks, guides carried by said compressor plates and in which said brace members have relative movement, and 5 manually actuated cam members carried by said compressor plates and cooperating with said brace members to lock said plates in closed position.

10. In a device of the character described, a frame, centering means, follower blocks guided and centered by said centering means, compressor plates hinged at their lower ends to said follower blocks, means to lock said follower blocks with respect to 15 said member, brace members hinged to said follower blocks, guides on said follower block through which said brace members pass, manually actuated cams carried by said compressor plates and cooperating with

said brace members to lock said plates in 20 closed position, and stops for said cams carried by said compressor plates.

11. In a device of the character described, a frame, a supporting member therein, follower blocks slidable on said member, compressor plates hinged to said follower blocks, brace members hinged to said follower blocks and guided on said compressor plates, locking means for said follower blocks, and means cooperating with said 25 brace members to lock said compressor plates in closed position, said supporting member, follower blocks, compressor plates and contents clamped therebetween being removable from said frame as a unit of 30 35 structure.

HENRY C. YEISER.
WILLIAM A. RINGLER.
